UNITED STATES PATENT OFFICE

CHARLES L. GOODRUM, OF ATHENS, GEORGIA, ASSIGNOR OF ONE-HALF TO LOUIS G. PACENT, OF NEW YORK, N. Y.

CONTROL CIRCUIT FOR SWITCHES FOR AUTOMATIC TELEPHONE SYSTEMS

Application filed March 31, 1932. Serial No. 602,190.

My present invention has for its object to provide a circuit arrangement for controlling the stepping movement of switches used in automatic telephone systems and their release, together with additional mechanism desired to automatically furnish ringing current to the called party's line and provide a busy test for preventing either of the connected lines from interference during conversation.

More specifically my invention provides for the accomplishments of these functions by the creation of current impulses over the two wires leading from a telephone subscriber's station by means of relays, or their equivalent, located in the two sides of the subscriber's line and other associate relays operating in conjunction with them and with the motor and release magnets of the switch. The first two mentioned relays are simultaneously energized and retained in this condition while the line is in use, the contacts controlled by said relays being influenced and one of them being caused to vibrate in response to a subscriber's impulse-transmitter which opens and closes the telephone circuit while the other is held in its closed or attracted position. Especial attention is given to the manner in which the contacts of the impulse transmitter, or dialing device, are arranged and also to the battery connections leading therethrough and supplying the control relays with current so that the main control relay contacts are closed upon the closure of the telephone circuit and remain closed during the vibrations of the contacts on the associate relay which intermittently actuates the motor magnet. By this arrangement the associate control relay is found to be upon the dry or grounded side of the line which adds to the fidelity with which it responds to the dialing impulses and the two control relays are not readily effected by a loss of current in the event leakage occurs in one or other of the line conductors.

To these and other ends my invention embodies further improvements all of which will be fully described in the accompanying specification the novel features being particularly pointed out in the appended claims.

In the drawings:

Fig. 1 is a diagrammatic view showing a circuit arrangement disclosing one embodiment of my invention; Fig. 2 is a fragmentary illustration showing a front elevation of a simple form of switch by reference to which an understanding of the operation of the circuits will be facilitated; Fig. 3 is a cross-sectional view on the line 3x—3x of Fig. 2; and Fig. 4 is a detail view showing the arrangement of the contacts of the subscriber's impulse transmitter.

Similar reference numerals of the several figures indicate similar parts.

In the present day automatic telephone systems operating on the so-called two wire principle a single impulse relay is utilized in connection with two slow release relays and considerable difficulty is experienced due to the necessity of carefully adjusting the period of dwell of the vibrating contact or armature of the impulse relay on its forward and back strokes; maintaining an accurate timing of the subscriber's impulse transmitter and supervision of the subscriber's line to prevent current loss by leakage on one or both of these conductors. Moreover in this arrangement inaccuracies in the operation of the switches occur due to the difficulty experienced in maintaining a proper current saturation in the cores of the slow releasing relays over the entire period required to dial the larger digits such as the Figures 7, 8 and 9. A further difficulty is also encountered in that a comparatively high voltage is required on the telephone lines to operate the switch relays and magnets which adds to the maintenance and operating costs.

An object of my invention is to provide a system which will operate satisfactorily on a line voltage less than one-half of that now employed and which is not effected by a comparatively slow transmission of impulses or an irregular transmission of such impulses from the subscriber's dialing mechanism and which is not effected by the usual or more commonly experienced current leakage on one or both sides of the telephone circuit.

In accordance with my invention I provide a new arrangement of the dialing contacts and the control relays in the subscrib-

er's circuit and I eliminate the use of the slow release relay heretofore employed for controlling the release magnet circuit of the switch, and I further provide a certain new 5 circuit combination for governing the stepping and releasing movements of the switches.

Before referring in detail to the improved circuit a type of switch which will facilitate 10 this description will be briefly explained. In Figs. 2 and 3 I have shown schematically certain necessarily associate parts of a switch construction comprising an arcuate terminal bank in which insulated terminals are arranged 15 in sets such as indicated by 1, 2 and 3 (Fig. 3) the first two comprising terminals for an incoming subscriber's line wires and the third being for a busy test circuit for such line. In practice it will be understood 20 that where the system is extended to a point where more than one switch is required for interconnecting a large group of subscriber's lines, additional switches are provided and these terminals are connected in multiple or 25 the switches are otherwise disposed to provide for the required classification of service. Rotatably mounted in front of the terminal bank are the cooperating switch wipers 1a, 2a and 3a carried on a journal 4 to 30 which is fixed a ratchet wheel 5. Spring fingers 1b, 2b and 3b extending inwardly from a support 6 engage the hubs of the wipers. A coil spring 7 of the required tension is connected to the journal 4 and its supporting frame serves to restore the switch wipers 35 to their normal position when they are released as indicated in Fig. 2. The switch is further provided with sets of off-normal contact springs 8, 9 and 10 which are arranged 40 above and at one side of the ratchet wheel 5 on a support or bracket 11. Mounted in conjunction with these springs is an operating finger 12, extending into the path of a pin 5a which when the switch is advanced releases 45 these sets of contacts. When the switch is in its normal position springs 8 and 9 are closed against their cooperating contacts 8a and 9a and spring 10 is disengaged from its contact 10a. The position of each 50 of these several contacts is reversed as soon as the switch is advanced one step.

In Fig. 4 I have shown diagrammatically a suitable arrangement of the contacts comprising part of the subscriber's dialing device 55 or transmitter. The latter further comprises a rotary driving member 13 adapted to be driven in one direction by the tension of a spring 14. An oscillatory setting member in the form of a ratchet wheel 13a is directly 60 connected to the spring and when it is restored to its original position causes the actuator 13 to be driven through the pawl 13b. The dialing device also embodies a series of contacts two of which are make contacts and 65 two of which are break contacts their assem-

bly being such that the making contacts are closed before the breaking contacts are open. Illustrative of these features I have shown three springs 16, 17 and 18 supported in a holder 19. Spring 17 has a tip 17a resting against spring 16. Beneath the latter is the spring 18 carrying on its upper side a contact 18a and on its lower side a stud 18b which when acted upon by the rotatable member 13 will close the contact 18a to first engage the spring 16 and thereafter elevate it to break the connection between the points 17a and 70 18b.

The subscriber's telephone line when in use 80 extends through the normally closed contact springs 16 and 17 as shown in Fig. 1 in which the line conductors are indicated by A and B in one of which is located the subscriber's telephone apparatus comprising the transmitter T, receiver R and the usual switch hook contacts H.

The subscriber's circuit extends through 90 relay contacts to be further described and terminates in the switch wipers 1a and 2a. In order that this line may be called by other subscribers terminals are allocated to it on the switch bank. For the purposes of description I have also illustrated in Fig. 1 a called party's line A² and B² which represents one 95 of several which terminate on different sets of switch terminals 1, 2 and 3. If the system requires two or more switches (a second switch being indicated at E) the corresponding terminals of the various lines are connected 100 in multiple as will be understood.

In a telephone system designed to accommodate a considerable number of subscribers, it is desirable to use a proportional number of switches which are very much less in number than are the lines which are served, and to provide for the automatic selection of one of the group of lines on which a call may be initiated. This is accomplished by a finder switch the function of which is to connect the calling line to an idle trunk leading to a 110 connector switch over which the desired connection can be effected by the transmission of the required number of impulses representing digits to advance its wipers into engagement with the terminals of the called party's line. To this end the line wires from the subscriber's station A appear as terminals A³ B³ of a line finder switch F to which the conductors A and B are joined by wires A⁴ and B⁴. The wipers f' and f² of the finder's 115 switch are terminals of a trunk, comprising the conductors A⁵ B⁵, leading to the connector switch control mechanism at which point they lead through the main control relay A' and its associate control relay C. The effect of 120 the connection of the line finder switch F is to extend the calling line and to place the control relays of the connector switch in direct connection with the two sides of the subscriber's circuit and also to extend said cir- 125 130 135

cuit beyond this point, by conductors A⁶ B⁶, through relays which are actuated when the called party answers so that a talking connection is established between the calling and 5 called party's stations through the advanced position of the connector switch wipers.

The function of the contact spring 18 of the impulse transmitter is to provide means for furnishing a ground connection to one 10 of the two conductors of the subscriber's line and to this end it is grounded at the subscriber's station as indicated at 18c. In this grounded side of the line I provide a main operating relay A' which is in circuit with 15 battery X which is the usual central office storage battery having a grounded connection x' leading from its positive pole. I arrange in the other conductor B an associate control relay c which is grounded as indicated 20 at c' or connected to the opposite pole of the battery from that to which relay A' is connected. A common battery is employed for supplying all of the circuits which are referred to but in order to simplify the illustration 25 separate batteries are shown with appropriate ground connections which indicate a common return for the several circuits.

The main and associate central relays may be of a similar construction but as the main 30 relay is on the wet or battery side of the line it will when energized operate to close a pair of contacts a² and the associate relay on the dry side of the line, serves to open a pair of contacts c². The contacts a² apply a 35 grounded connection a³ through conductor 20 to the contacts c² which control the stepping movement of the motor magnet of the switch in response to impulses transmitted by the action of the subscriber's dialing device. 40 The main and associate control relays are simultaneously energized and the spring 18 maintaining a battery connection through the main control relay when the contacts 16 and 17 are disrupted will retain its contacts a² 45 closed continuously while the receiver switch hook contacts are closed.

For advancing the switch I employ a motor magnet M having an armature m which is attracted against the tension of a spring m' 50 and carries a pawl or finger m² which engages with the teeth of the ratchet wheel 5 to advance the switch wipers one step upon each impulse of current transmitted to the magnet.

55 In order to lock the switch in its operated position, and subsequently permit it to be restored to its normal position, I arrange the release magnet L and its circuit in such a manner that it is capable of performing both 60 of these functions. The release magnet has a pivoted armature l carrying a detent or dog l' which is normally held out of engagement with the ratchet wheel 5 when in the retracted position by a pin l². Upon the attraction of 65 the armature of this magnet the pawl is re-

lieved and allowed to move upwardly under the influence of a spring l². The relay magnet L is connected at one terminal to battery X' and at its opposite extremity to the conductor 21 leading to contact 8a of the off-normal spring 8. From spring 8 a conductor 22 leads to conductor 20. Hence it will be seen that when the main relay is initially energized by closure of the subscriber's line the magnet L is energized so that the pawl l' 70 engages the first ratchet tooth and as the ratchet wheel 5 is subsequently advanced it will be held in the operated position. In order to hold magnet L energized after the off-normal contacts 8 and 8a are broken 75 a branch circuit is provided, as indicated by the wires 23 and 24 which extend to a pair of contacts L' which are closed upon the energization of magnet L and thereafter serve to bridge the first mentioned contacts 8 and 8a 80 in this circuit.

The motor magnet is intermittently energized by the closing of the contacts c² on the associate control relay C, but as this relay remains energized over the closed subscriber's circuit after the transmission of the last impulse from the dialing device, it is necessary to provide in the circuit of the motor magnet means for maintaining its continuity 90 during the period the impulses are being transmitted, said means being so arranged that it is actuated upon the first impulse transmitted and disconnected automatically upon the completion of the group of impulses. To this end I provide in the motor magnet circuit a separate control relay O. This is a slow to release relay, the core of 95 which is provided with a copper sheath or equipped with a copper slug which will serve to retain the magnetism therein and delay the opening of its contacts after the circuit of the relay is opened. One terminal of this relay is connected by conductor 25 to the off-normal contact 9a from which a circuit 100 extends through spring 9 by way of wire 26 to the back terminal of the impulse contacts c². The other terminal or relay O is connected by conductor 27 to motor magnet M which receives current impulses from battery X².

A pair of contacts o' on relay O are closed 105 when this relay is energized and after the first step of the switch bridge the opening in the circuit created by the opening of the off-normal contacts 9 and 9a. Consequently, upon each closure of the associate control relay contacts c² an impulse of current transverses the motor magnet M and its associate relay O through the bridging contacts o'. The impeded movement, or sluggish release operation of the relay O causes it to hold over during the rapid vibration of contacts c² and it only releases its sustaining circuit contacts o' 110 when the contacts c² are open permanently.

In order that the calling subscriber's line 115 may be rendered busy and access thereto pre-

vented after a subscriber has set up a connection with a desired called party, I provide means for grounding the third or associate line terminal 3 of the switch through the 5 closed terminals a^2 of the main control relay A'. This busy circuit is rendered operative upon the cessation of movement of the motor magnet by providing on the motor control relay O a pair of contacts o^2 which are held 10 open while this relay is energized and when released serve to extend the circuit through the then closed pair of off-normal contacts 10 and 10a. The latter is connected by conductor 28 to the back contact of the pair of 15 contacts o^2 , the armature of which is connected by wire 29 to conductor 24 grounded at a^2 . Leading from spring 10 is a conductor 30 connected to back contact 31 which is engaged by an armature 32 from which extends 20 conductor 33 terminating in the switch wiper 3a. When the switch is in its normal position contacts 10 and 10a are open so that subscriber's line A-B is free for selection by any other calling party, but after this line has 25 completed a call a grounded condition of switch wiper 3a is effected so that an attempted selection of the corresponding set of terminals on which the connector wipers rest will cause the calling party to receive 30 the busy test signal and also render it impossible for him to connect with the busy line.

Upon each impulse to the motor magnet there is closed simultaneously with the movement 35 of its armature a pair of contacts m^3 , the armature of which is connected to ground as indicated at m^4 , its forward contact being joined by the conductor 35 to one winding of the busy test relay P which is fed by battery 40 X³ the function of which is to prevent the passing of ringing current as the switch wipers step over successive sets of line terminals. There are two windings on the busy test relay indicated by p and p' both of which are connected to the battery X³, and additional contacts p^2 and p^3 , the latter cooperating with the armature 32 and serving to keep relay P energized when the switch wiper 3a is advanced into engagement with a grounded or 45 busy terminal of a called line.

The ringing current for signaling the called party's line is controlled by the ringing relay Q supplied with current from the battery X⁴ and its circuit terminates in the 55 back contact q of armature q' which in its forward movement engages the forward contact p^2 of the busy test relay. The ringing current apparatus may be an alternating current ringing machine N and a source of direct current N' the circuit for which terminates in armatures q^2 , q^3 on the relay Q. When the latter is energized said armatures engage with forward contacts which in turn are connected to the called party's line by the conductors 36 and 37. A transformer N² has

its two windings included in the A. C. and D. C. circuits just mentioned so that the A. C. ringing current is dispatched when the armatures q^2 , q^3 are attracted. In order that this ringing current may be applied intermittently there is placed in the A. C. circuit a commutator n' . 70

Before tracing this ringing circuit reference should be made to additional instrumentalities by which the calling party's circuit is cut through in such a way that when the called party answers the ringing interruptions are automatically discontinued. The cut through relay S is supplied with current from a battery X⁵ through the resistance s and by means of the conductor 38 (which is a continuation of conductor 30), the completed circuit may be traced to the ground a^3 through the closed main control relay contacts a^2 . However, in order to prevent this circuit from causing the magnet to be energized before the called party answers said relay is short circuited through one of its own contacts and a pair of contacts on the ringing trip relay T. The cut through relay S is provided with an armature s' connected to the switch wiper 1a by wire 39 and a similar armature s^2 connected to wiper 2a by wire 40. Armature s' normally engages its back contact s^3 connected by a wire 41 with one terminal of the winding of the trip relay T, the opposite extremity of which is connected to one of the ringing conductors 37. The second armature s^2 normally engages the back contact s^4 which is the terminal of the other ringing conductor 36. A third armature s^5 is mounted on the relay S engaging a back contact s^6 which is also connected to the conductor 38. On the relay T is an armature t engaging the back contact t' . The armature t is connected by the conductor 43 to battery X⁵ through resistance s and the armature s^5 and back contact t' are joined by the conductor 44. By tracing the circuit from grounded conductor 38 through contact s^6 , armatures s^5 conductor 44, contact t' , armature t , wire 43, resistance s to battery X⁵ and ground it will be seen that while the ringing trip relay T is deenergized ringing current will be transmitted to signal the called party's line 100 because a short circuit exists to render the cut through relay S inoperative. When the called party answers the relay T is energized and the attraction of the armature t opens the short circuit and permits the relay S to operate to attract its series of armatures. The pulling up of the armatures s' and s^2 connects the conductor 39 and 40, leading from the switch wipers, to forward contacts 110 s^7 and s^8 from which lead conductors 45 and 46 to armatures u and u' on the called party's answering relay U. The forward contacts of these armatures are terminals for the calling line A-B. The relay U is provided with two windings u^2 and u^3 each of which is con- 115

120 125 130

nected at one end to the conductors 45 and 46 and at their opposite extremities to the two poles of the battery X^e . Consequently these armatures are attracted simultaneously 5 with the armatures of the cut through relay S and the calling party's line is extended through the switch wipers to the called line. Upon the called party answering his line is closed at the switch hook contacts H^2 and the current which then flows over it from battery X^e holds the armatures u , u' and s , s' closed to permit conversation to be carried on between the two telephone stations.

If the called party's line is in use the 15 switch wiper $3a$ comes to rest on a busy or grounded terminal with the result that a circuit is established through the battery X^s , the winding p' and the armature 32 before the latter is released from the position in 20 which it was attracted when the winding p is energized by the closing of the test contacts m^s upon each step of the motor magnet. The retaining of the busy test magnet energized by the ground picked up by switch wiper $3a$ 25 opens the circuit of the ringing relay Q by holding the armature q attracted. The busy test relay P under these circumstances applies a busy tone to the calling party's line from a specially designed commutator V, a circuit for which is closed by the armature v on relay P to dispatch the busy signal over 30 a conductor 49 to the calling subscriber's line.

What I claim is:

1. In combination with two telephone line 35 conductors, a source of current therefor, an impulse transmitter having a pair of contacts through which said line is normally closed and a normally open contact connected to said source and adapted to maintain current through one conductor while the current through the other conductor is intermittently discontinued, of a main control relay in the first mentioned conductor having a normally open pair of contacts, an associate control relay in the other conductor having a pair of closed contacts, and a switch comprising a motor magnet having a circuit extending through said pairs of contacts.

2. A telephone switching system comprising 50 telephone line circuit conductors each having a control relay provided respectively with normally open and normally closed pairs of contacts, an impulse transmitter having a pair of breaking contacts and a pair of making contacts, a source of current normally maintained over the telephone circuit by said breaking contacts and supplied to one side of said circuit by the closure of the making contacts, a switch having a motor magnet provided with an operating circuit controlled jointly by said control relays.

3. A telephone switching system comprising 55 an impulse transmitter having a pair of closed breaking contacts and a pair of open making contacts arranged to operate in uni-

son with the latter contacts closing before the former open, a telephone line normally closed through the first mentioned contacts and comprising two control relays each provided with sets of contacts, a source of current for the telephone line also connected to the making contacts of the transmitter, a switch having a motor magnet provided with a circuit controlled by said control relays upon the operation of said transmitter.

4. A telephone switching system comprising 60 an impulse transmitter having a pair of breaking contacts and a pair of making contacts and means for alternating the positions of said contacts, telephone line conductors connected to said contacts whereby the circuit through the two conductors is normally closed through the making contacts and one of said conductors is subsequently closed through the making contacts, a pair of control relays in the two sides of the telephone circuit, a source of battery current connected to the two conductors with the dry side thereof leading through the making contacts of the transmitter, and a switch having a motor magnet provided with a circuit controlled by 65 said control relays.

5. In a telephone system, the combination 70 with a telephone line, a control relay having a pair of contacts and an impulse transmitter in said line, a switch comprising a movable element, and a pair of off-normal contacts which are closed by the switch when in its normal position, of a motor magnet provided with a circuit leading through the control relay contacts and through the off-normal contacts and a bridging relay in the motor magnet circuit having a pair of contacts which are closed by the action of the control relay to bridge the off-normal contacts.

6. In a telephone system, the combination 75 with an impulse transmitter, a pair of telephone circuit conductors leading therethrough and a control relay in one of said conductors having a pair of contacts adapted to vibrate in response to the transmitter, of a switch having a movable element, a pair of contacts closed thereby when the switch is in its normal position, a slow releasing relay 80 having a pair of contacts and adapted to be energized upon the first impulse dispatched upon the action of the transmitter, and a motor magnet for driving the switch having a circuit leading through the slow relay contacts and the off-normal contacts on the first impulse transmitted and subsequently receiving impulses through the slow relay contacts.

7. A telephone system switching mechanism comprising an impulse transmitter, a subscriber's circuit leading therefrom, a control relay therein having contacts vibrating in response to said transmitter, a switch comprising a motor magnet, a pair of contacts closed by the switch in its normal position, a 85

slow releasing relay having an open pair of contacts which are adapted to be closed and remain closed by the energization of said relay in response to the action of the transmitter, a 5 circuit for the motor magnet leading through the slow relay winding and through its contacts and the off-normal switch contacts.

8. A telephone switching mechanism comprising an impulse transmitter, a telephone 10 circuit leading therefrom having receiver-hook contacts, a switch and means for driving it in response to the circuit interruptions created by said transmitter, a control relay in said circuit having a pair of contacts which 15 are held closed while said telephone circuit is closed at said hook contacts, a pair of off-normal contacts which are held closed when the switch is in its normal position, a release magnet operating to hold the switch against 20 retrograde movement upon the closure of the telephone circuit, a pair of binding contacts for the release magnet circuit which are closed by the energization of the release magnet, a circuit for the release magnet leading 25 through the normally closed switch contacts and the control relay contacts in the first instance and having a branch extending through said holding contacts which maintains said magnet energized while the telephone circuit is closed at its hook contacts.

9. A telephone switching mechanism comprising an impulse transmitter, a telephone circuit leading therefrom having receiver hook contacts, a control relay in said circuit 30 having contacts which are closed in unison with said hook contacts, a switch having a pair of closed off-normal contacts which are open upon movement of the switch, means for stepping the switch in response to the action of the transmitter, a release magnet 35 adapted to be actuated upon the closure of the telephone circuit to hold the switch against retrograde movement, a circuit therefor leading through the off-normal contacts and 40 the contacts of the control relay to energize the release magnet in the first instance and means for maintaining the release circuit energized continually while the telephone circuit is energized.

50 10. A telephone switching mechanism comprising an impulse transmitter, a telephone circuit leading therethrough having receiver hook contacts, a control relay in said circuit having contacts which are closed in unison with said hook contacts, a switch 55 and means for driving it in response to the action of the transmitter, a pair of off-normal contacts which are closed by the switch in its normal position, a release magnet operating 60 to hold the switch against retrograde movement, a circuit therefor leading through the off-normal contacts and control relay contacts, and a branch circuit having a pair of contacts adapted to be closed to bridge the

off-normal contacts upon the energization of the released magnet.

11. A telephone system comprising a pair of subscriber's line conductors including a control relay and an impulse transmitter, a pair of contacts on the relay which are closed when the circuit through the conductor is closed, a switch, driving devices for operating it in response to the action of the transmitter, means for locking the switch against retrograde movement comprising a release magnet for actuating said means in unison with the closure of the subscriber's line, and a holding circuit for said magnet extending through the control relay contacts and including a pair of contacts which are closed coincidentally with the actuation of the release magnet.

12. A telephone system comprising a subscriber's line circuit, a control relay therein having a pair of grounded contacts which are closed in response to the closure of said line, an impulse transmitter on said line, a switch provided with terminals for the latter and also comprising a corresponding busy terminal, wipers cooperating with said terminals, means for driving the switch upon the operation of the transmitter comprising a motor magnet and a motor control relay having a pair of contacts which are closed when said relay is deenergized, mechanism for holding the switch against retrograde movement comprising a release magnet, a pair of off-normal contacts which are opened when the switch is in normal position, a busy-switch-indicating circuit extending from the busy terminal wiper through the then closed off-normal contacts and to ground at the control relay contacts upon cessation of the advancing movement of the switch.

13. A telephone switching system comprising an impulse transmitter having a pair of closed line terminals and free grounded contact, subscriber's line conductors connected to the closed terminals, means for operating the free contact to closed ground through one of said conductors and subsequently open the closed line terminals intermittently, a main control relay in the grounded side of the subscriber's line, an associate relay in the other side of said line, a source of current for said line, a pair of contacts closed by the main relay, a pair of contacts opened and released by the associate relay each time the circuit through the line conductors is interrupted, a switch mechanism comprising a motor magnet rendered operative by the main control relay and actuated step-by-step by the associate control relay.

14. A telephone switching system comprising an impulse transmitter having a pair of closed terminals and a free grounded contact and means for operating the latter to apply ground to one of the terminals of said pair and to separate them, subscriber's line con-

ductors connected to the pair of terminals, a main control relay in conductor which is adapted to be grounded by the free contact, an associate control relay in the other conductor, 5 a source of current for said line, a pair of grounded contacts closed by the main relay and a pair of grounded contacts vibrated by the associate relay in response to opening and closing of the line at said pair of transmitter terminals, 10 a switch mechanism comprising a motor magnet rendered operative by the main relay and actuated step-by-step by the associate relay, and a release mechanism embodying a release magnet which is energized to hold the switch against retrograde movement by the action of the main relay.

15. A telephone system comprising a switch having sets of line terminals each set including an additional busy terminal and cooperating switch wipers, a subscriber's impulse transmitter having a pair of closed contacts, an additional free grounded contact and means for operating the latter to connect 20 ground to one of the line conductors and to open the closed contacts momentarily, a pair of line conductors leading from said closed terminals respectively to said switch, a main control relay in the conductor thus grounded 25 by said additional contact, an associate relay in the other conductor, a source of current for said line and for operating the switch having a ground connection, a pair of contacts on the main control relay for closing the connection 30 from the source of current, a pair of contacts on the associate relay adapted to vibrate in response to interruptions of current in the subscriber's circuit, a motor magnet for stepping the switch on each of said current impulses, 35 a release magnet for holding the switch in its advance position having a circuit maintained during the operation of the switch through the ground established by the main control relay contacts, off-normal contacts 40 adapted to be closed when the switch is advanced, a busy test circuit extending from the busy test wiper through said closed off-normal contacts and the ground at the closed terminals of the main control relay.

45 50 In testimony whereof, I have signed this specification.

CHARLES L. GOODRUM.
